(57) **CLAIM**

The ornamental design for a passenger car, as shown and described.

DESCRIPTION

FIG. 1 is a front perspective view for a “passenger car” showing our new design,

FIG. 2 is a rear perspective view thereof,

FIG. 3 is a front view thereof,

FIG. 4 is a rear view thereof,

FIG. 5 is a top view thereof,

FIG. 6 is a left-side view thereof; and,

FIG. 7 is a right-side view thereof.

The bottom view of the passenger car forms no part of the claimed design.
